UNITED STATES PATENT OFFICE.

MARQUIS D. HANLON, OF WILKINSBURG, PENNSYLVANIA, ASSIGNOR TO THE UNION SWITCH AND SIGNAL COMPANY, OF SWISSVALE, PENNSYLVANIA, A CORPORATION OF PENNSYLVANIA.

RAILWAY-SIGNAL.

SPECIFICATION forming part of Letters Patent No. 729,065, dated May 26, 1903.

Application filed February 5, 1903. Serial No. 142,016. (No model.)

To all whom it may concern:

Be it known that I, MARQUIS D. HANLON, a citizen of the United States, residing at Wilkinsburg, in the county of Allegheny and State of Pennsylvania, have invented certain new and useful Improvements in Railway-Signals, of which the following is a specification.

My invention relates to railway-signals, and particularly to that class of railway-signals the signal device of which is adapted to give three indications.

I will describe a railway-signal embodying my invention and then point out the novel features thereof in a claim.

In the accompanying drawings, Figure 1 is a diagrammatic view of a portion of a railroad-track, showing a railway-signal embodying my invention applied to one of the insulated divisions of the railroad-track and also showing the necessary connections and apparatus employed in the system by which the mechanism of the railway-signal is controlled in its operation of the signal device. Fig. 2 is a view, partly in elevation and partly in vertical section, of a mechanism embodying my invention which is employed for moving the signal device to different positions of indication. Figs. 3 and 4 are detail views, in vertical section, showing different positions of the operating mechanism of Fig. 2. Fig. 2 is drawn to a scale different from that of Fig. 1, and Figs. 3 and 4 are drawn to a scale different from that of Figs. 1 and 2.

Similar characters of reference designate corresponding parts in all of the figures.

A designates a post or other suitable support, and B a signal device supported thereby.

The signal device B is here shown as being of the semaphore type and as comprising a blade b and a spectacle-casting b', to which the blade is secured and which also serves as a counterweight for the blade b. The spectacle-casting b' may be formed to carry as many lenses b² as desired in order that the signal device may be employed to give indications at night in connection with a lamp. The casting b' is fixed upon a shaft suitably journaled on the post, which shaft carries

an arm b⁵, to which one end of an up-and-down rod b⁶ is connected. The lower end of the rod b⁶ is connected to a lever b⁷, which is fulcrumed intermediate its ends. The lever b⁷ is adapted to be rocked or moved on its fulcrum by the operating mechanism or apparatus comprised in the railway-signal. As here shown, such mechanism is of the fluid-pressure type, and two such mechanisms D D' are preferably employed.

Each fluid-pressure mechanism is here shown as comprising a cylinder d and a piston d', which is movable within the cylinder d. As shown in the drawings and as a preferable arrangement, the mechanisms D D' are superimposed, the two mechanisms being suitably secured in a framework which is adapted for attachment to some stationary support. If desired also, an inclosing case may be provided for the mechanisms D D'. Fluid-pressure is supplied to the mechanisms from any suitable source, and the supply of fluid-pressure to each mechanism is under the control of an electrically-operated valve device E. The valve device may conveniently be substantially of the form and arrangement illustrated and described in United States Patent No. 357,109, issued February 1, 1887, to George Westinghouse, Jr., for electrical interlocking mechanism for switches and signals, to which patent reference may be had for details of construction and operation.

It is only necessary to here state that each electrically-operated valve device has the functions of opening the supply of fluid-pressure when the magnet comprised therein is energized and of shutting off or closing the supply of fluid-pressure when the magnet comprised therein is deenergized and to open an exhaust port or passage to the atmosphere.

The pistons comprised in the mechanisms D D' preferably have different lengths of stroke, and the piston in the upper mechanism is adapted to act directly onto the head of the piston in the mechanism beneath and through the stem of the last-mentioned piston to communicate its motion to the lever b⁷.

When the signal device is in the "clear" position of indication, which is that shown in Fig. 1, the positions of the pistons of the several mechanisms are as shown in Fig. 4. 5 When the signal device is in this position of indication, fluid-pressure is acting upon the pistons to hold them against any movement of the signal device acting under the influence of its counterweight. If desired, in the 10 clear position of indication the fluid-pressure may only be supplied to the mechanism D', and supplied to the mechanism D at a time when it is required that the signal device give another indication. If the fluid- 15 pressure is cut off from the fluid-pressure mechanisms, the counterweight b⁶ will tend to move the rod b⁶ downwardly and to move the piston in the cylinder to the positions shown in Fig. 2. With the piston in this position the signal device will display a "danger" indication, this being the indication when the signal device is in the horizontal position. If now the magnet in the valve device E, controlling the supply of fluid- 25 pressure to the mechanism D, be energized, fluid-pressure will operate the piston thereof to move it to the other end of the cylinder, (see Fig. 3,) and this movement of the piston is transmitted by the piston of the mechanism D' to the lever b⁷. With the pistons in the position shown in Fig. 3 the signal device will occupy a "caution" position of indication, the blade for this indication occupying a position midway between its danger 30 position of indication and its clear position of indication. If now the magnet of the valve device E, applied to the mechanism D', be energized to admit fluid-pressure to its mechanism, the fluid-pressure will move the piston to the lower end of the cylinder, (see Fig. 4,) which movement of the piston will operate to move the signal device to the clear position of indication, which is shown in Fig. 1. 35

It will be understood that to move the signal device from the danger position of indication to the caution position of indication fluid-pressure is admitted to the upper cylinder d', and to move the signal device to the clear position of indication either from the 40 danger position or from the caution position fluid-pressure is admitted to the cylinder d². The signal device may be moved from the clear position to either the caution or danger positions by cutting off the supply of fluid- 45 pressure from one or both cylinders.

In Fig. 1 I have diagrammatically illustrated a railway signal system which includes a railway-signal made in accordance with my invention. The system illustrated is what is 50 known as the "polarized" system—that is, a system which includes for each "block" or insulated section of track a magnet having a neutral and a polarized armature and a pole-changer, the function of which is to change 55 the direction of current from the track-battery through the magnet. The pole-changer of one block, as is well known, is operated

from the railway-signal of the succeeding block. The line of railway-track is shown divided (by suitable insulations) into two 70 blocks or sections X and Y. The block Y is provided at its entrance end with a relay-magnet R, having a neutral armature r and a polarized armature r'. The other or exit end of the block is provided with a battery S, 75 electrically connected to the rails of the block through a pole-changer P, which is mechanically connected with the signal device B of the railway-signal 2, which controls the entrance of trains into the block Z. With no 80 train or pair of wheels in the block Y and the signal device B of railway-signal 2 in the clear position of indication the neutral armature r will be against contact 3 and the polarized armature will be against a contact 4. The armatures r and r' and the contact-points 3 and 4 are included in separate local circuits, which circuits include the valve devices E, and when both armatures are against their front contacts both magnets in the valve devices E will be energized and fluid-pressure will enter the cylinders d to operate the pistons therein. When both armatures are away from their contacts, due to the short-circuiting of the battery S—as, for example, by a train or a 95 pair of wheels—both local circuits will be opened and the fluid-pressure cut off from both the cylinders, and with the fluid-pressure cut off the signal device will assume a danger 100 position of indication through the influence of its counterweight. As the train passes into the next block the same operation above described takes place; but the movement of the signal device B of railway-signal 2 will operate the pole-changer in such manner as 105 to have the current pass through the relay R in a direction to allow it to pick up its neutral armature r, but not to affect its polarized armature r'. With the armature r against the contact 3 the circuit through the valve 110 device E of the mechanism will be closed and the valve device actuated to admit fluid-pressure to the cylinder d and have the piston move the signal device of railway-signal 1 to caution position. The movement of signal 115 device B of railway-signal 2 to the caution position of indication will cause a further movement of the pole-changer P, which in turn will direct the current through the relay R in such direction as to have it move 120 its polarized armature r' against the contact 4 to close the circuit through the magnet of valve device F² and have it admit fluid-pressure to the cylinder d², the piston of which will move the signal device B of signal 1 to 125 the clear position of indication.

It is obvious that other forms of connection between the fluid-pressure mechanisms and the up-and-down rod b⁶ may be employed instead of the lever b⁷.

What I claim as my invention is—

In a railway-signal, the combination of a signal device, a plurality of fluid-pressure mechanisms for moving the signal device to

different positions of indications, the pistons of which have different lengths of stroke, said fluid-pressure mechanisms being superimposed and the piston of one fluid-pressure mechanism being adapted to move the signal device to one position of indication and to bear upon the piston of another fluid-pressure mechanism to move it, and the piston so moved by the first-mentioned piston being adapted to move the signal device from either of two positions to a different position of in-

dication, and an electrically-operated valve device for controlling the supply of fluid-pressure to each of the fluid-pressure mechanisms.

In testimony whereof I have signed my ¹⁵ name to this specification in the presence of two subscribing witnesses.

MARQUIS D. HANLON.
